CLAIM

The ornamental design for a removable skateboard handle post with adjustable fold-out seat, as shown and described.

DESCRIPTION

FIG. 1 is a rear, top and side perspective view of a removable skateboard handle post with adjustable fold-out seat showing my new design, the broken lines illustrating a skateboard are for illustrative purposes and form no part of the claim;

FIG. 2 is a top plan view;

FIG. 3 is a rear elevational view;

FIG. 4 is a right side elevational view, the opposite side being a mirror image thereof;

FIG. 5 is a front elevational view; and,

FIG. 6 is a bottom plan view.
